Inventor
Hugo Krüger
By his Attorney
George C. Heinrichs

UNITED STATES PATENT OFFICE

HUGO KRÜGER, OF HOBOKEN, NEW JERSEY

FOLDING UMBRELLA

Application filed September 27, 1927. Serial No. 222,312.

This invention relates to improvements in umbrellas, parasols or the like, and it is the principal object of my invention to provide an umbrella allowing the folding thereof into a very small compass.

Another object of my invention is the provision of a foldable and collapsible umbrella allowing a telescoping of its ribs, and stick, and a folding of its spreaders against the telescoped ribs, so that the umbrella may be conveniently carried in a pocket.

A further object of my invention is the provision of a folding umbrella of extremely simple and therefore inexpensive construction, yet durable and efficient in operation, and equipped with suitable locking means for effectively locking the parts in their relative adjusted position in the extended as well as in the folded position of the umbrella.

A still further object of my invention is the provision of a foldable or collapsible umbrella allowing a neatly folding of its cover material against and between the stick and ribs when the entire umbrella is folded into its smallest compass.

These and other objects and advantages of my invention will become more fully known as the description thereof proceeds, and will then be more specifically defined in the appended claim.

In the accompanying drawings, forming a material part of this disclosure:-

Figure 1 is a sectional elevation of an umbrella constructed according to my invention, extended.

Figure 2 is a view showing the bayonet lock.

Figure 3 is a similar view with the umbrella collapsed and folded.

As illustrated, the shaft or stick 10 of the umbrella carries at its lower end a handle 11 and is hollow for the reception of the upper rod 12 which carries at a certain distance from its upper end a crown or collar 13 to which the inner ends of hollow ribs 14 are secured in the well known customary manner to allow a folding of the same against the rod.

These ribs 14 have the form of hollow cylinders equipped with longitudinal slots allow-

ing the passage of the eyes 16 and their displacement therein. Into the cylindrical ribs 14 extend the inner ends of ribs 17 to which the eyes 16 are attached and which are telescopically displaceable within the ribs 14.

To the eyes 16 are attached in the usual well known manner, the outer ends of the stretcher or spreader rods 18, the inner ends of which are attached to a sleeve 19 slidably arranged on rod 12 and slotted in its side face to allow in the customary well known manner the passage of a spring-controlled dog 20. A similar dog 22 locks the sleeve in its lowermost position.

The rod 12 is telescopically displaceable into the stick, and a collar 21 near its extreme outer end limits its inward movement.

The handle 11 is attached to the stick 10 by means of a bayonet lock 22' adapted to be engaged by dog 22, so that stick and rod may be held in place when the umbrella is opened, as indicated in Figure 1.

A spring-controlled dog 23 is provided near the inner face of the umbrella roof for the purpose of engaging and passing through the slot 22' of the bayonet lock when the shaft and rod are telescoped to prevent a separation of the parts in the telescoped position as shown in Fig. 3.

The operation of my device will be entirely clear from the above description.

If it is desired to fold the umbrella, the dog 20 is pressed inwardly in the usual, well known manner, and the sleeve 19 is moved downwards along rod 12 and stick 10. This movement by means of the spreaders 18 draws the cylindrical rods 14 down and by the displacement of the eyes 16 which are secured the ribs 17 draw the same into the rods 14.

When then the handle 11 and stick 10 are given a turn in order to allow a relative movement of rod 12 and stick 10 to release the bayonet lock, the rod 12 can be telescoped into the stick, and its point is prevented from entering into the folded umbrella by its collar 21. Thus, the umbrella 15 is capable of folding into a very small compass of about 12 inches and may be conveniently carried in the pocket. The parts in their folded position

are securely held against separation by the engagement of dog 23 in the bayonet slot 22' near the upper end of stick 10.

While I have described the preferred form 5 of my device as an example, it is to be understood that I may make such changes in the specific arrangement and in the construction of the minor details of my invention as come within the scope of the appended claim without 10 departure from the spirit of my invention and the principle involved.

Having thus described my invention what I claim as new, and desire to secure by Letters Patent is:—

- 15 In a folding and collapsible umbrella, a hollow stick, a rod adapted to telescope into said stick, said stick having a bayonet slot formed near its upper end, and a spring controlled dog on said rod adapted to pass through 20 the bayonet slot when the umbrella is folded and collapsed to prevent separation of the parts and another dog on said rod to engage said bayonet slot when the umbrella is opened to limit the outward movement of said rod.
- 25 Signed at New York, in the county of New York and State of New York, this 23rd day of September, A. D. 1927.

HUGO KRÜGER.
